CRANE FOR THREE-POINT MOUNTING

Rawlen T. Smith, 4170 Dover St., Wheatridge, Colo.

Filed Feb. 5, 1965, Ser. No. 83,699

Term of patent 14 years

(Cl. D41—1)

Fig. 1

Fig. 2

Fig. 3

FIG. 4

FIG. 5

FIG. 1 is a side elevation of the crane for three-point mounting of the invention embodying my new design;

FIG. 2 is a front elevational view of the crane of the invention;

FIG. 3 is a top plan view of the crane of the invention;

FIG. 4 is a front quarter perspective of the crane according to the invention; and

FIG. 5 is a rear quarter perspective of the crane of the invention.

The broken line showing is for illustrative purposes only.

I claim:

The ornamental design for a crane for three-point mounting, as shown and described.
